UNITED STATES PATENT OFFICE.

JOSEPH N. THOMAS, OF JOHNSTOWN, PENNSYLVANIA, ASSIGNOR TO THE JOHNSON COMPANY, OF LORAIN, OHIO.

MAGNETIC CLOSER.

SPECIFICATION forming part of Letters Patent No. 599,881, dated March 1, 1898.

Application filed October 19, 1897. Serial No. 655,658. (No model.)

To all whom it may concern:

Be it known that I, JOSEPH N. THOMAS, of Johnstown, in the county of Cambria and State of Pennsylvania, have invented a new and useful Improvement in Magnetic Closers, of which the following is a full, clear, and exact description, reference being had to the accompanying drawings, which form a part of this specification.

My invention relates to magnets of that type which are carried by electric vehicles to actuate a current-conveyer placed between the bared working conductor and the source of supply. In railways in which traveling magnets of this character are used there is danger of the magnet-pole acting to short-circuit one of the bared conductor-contacts to the rails of a crossing track, because the track-rails are generally connected to the opposite side of the circuit to that with which the aforesaid contacts are connected. This short-circuiting may be established either by small pieces of magnetic material being picked up by the magnet, so bringing the poles of the magnet into direct connection with a contact or crossing rail, or both, or it may be established by unevenness of the track or poor adjustment of the position of the magnet, which might allow the latter to come into direct contact with the parts of the circuit mentioned. The object of my invention is to avoid this danger by providing a magnet which will have the substantially continuous magnetic fields, which are desirable, but which will at the same time be composed of electrically-disconnected sections.

Referring to the accompanying drawings, Figure 1 is a plan view, Fig. 2 a side view, and Fig. 3 a transverse section, of a magnet embodying the features of my invention. Figs. 4 and 5 are enlarged sections showing the means I employ for the construction of the magnet-poles. Fig. 6 is a perspective view of a modified form of construction which also embodies the general principle of my invention. Fig. 7 is a sectional view of the same, and Fig. 8 is a section of one of the poles of the magnet.

The particular magnet which I have shown is made of a plurality of yokes A, surrounded by energizing-coils B, having their ends con-

nected by pole-pieces in such a manner as to form one magnet having two longitudinal parallel poles.

In the preferred form of construction which I show in Figs. 1 to 5, inclusive, the lower ends of the cores A are secured by suitable countersunk screws s (see Fig. 3) to plates of magnetizable material, as a'. a and a² are plates of similar material which are secured to plates a' by means of bolts d and e. A construction similar to this is employed throughout the length of the pole-piece—that is to say, there is an upper layer of plates a' a² a⁵, &c., and a lower layer of plates a³ a⁴, &c., secured to the upper layer by means of bolts, as d and e. Between the upper and lower set of plates is the insulation C, such as sheet-rubber. As will be noted, this insulation not only is placed between the upper and lower plates, but its ends are brought upward or downward, as the case may be, so as to insulate adjacent plates of the same layer, such as a' from a² or a from a³. I preferably place this insulation so that the joints in the upper and lower layers will be staggered. The insulation between the different members of the upper layer is not absolutely essential.

Referring to Fig. 4, e is a tap-bolt which screws into the upper layer of plates, as a', and is insulated from the lower layer, as a, by a suitable insulating compound e', cast about the bolt.

Referring to Fig. 5, d is a tap-bolt which screws into the lower layer of plates, as a, and is protected from the upper layer of plates, as a', by the molded insulating compound d'. It is of course obvious that I may, if desired, use the construction shown in Fig. 4 for all the fastenings. With this form of magnet it is clear that I entirely avoid the danger of short-circuiting the railway system under the conditions which I have previously set forth. At the same time I do not weaken the magnetic field to any appreciable extent, for the magnetic lines are distributed over such a large surface area when passing through the insulator C that the loss is inappreciable.

On Sheet 2 of the drawings I illustrate another form which my invention may take. In this form I provide a plurality of channel-irons A', connected by rivets to continuous

wooden blocks C' and separated by suitable insulators C², such as fiber or mica. Under some circumstances this form of magnet might be desirable, for it is very simple and may be cheaply constructed. It has not, however, as good a magnetic path as the magnet shown on Sheet 1, and I therefore generally prefer to use the latter.

It is clear that I am not limited to the particular details described, for I believe that it is broadly new to provide a magnetic closer having a longitudinal pole which is substantially continuous magnetically, but discontinuous electrically, and it is my desire to claim this feature regardless of the particular details of construction by which it is obtained.

Having thus described my invention, what I claim, and desire to protect by Letters Patent, is—

- 20 1. A magnetic closer having an extended pole adapted to supply a substantially continuous magnetic field throughout its length and composed of a plurality of sections insulated from each other.
- 25 2. A magnetic closer having a longitudinal pole adapted to supply a substantially continuous magnetic field throughout its length and composed of electrically-disconnected sections.
- 30 3. A magnetic closer comprising a plurality of cores and energizing-coils for the same, in combination with continuous members secured to the ends of the cores and composed of a plurality of electrically-disconnected sections.
- 35 4. A pole-piece for a magnetic closer com-

posed of adjacent parallel layers, each layer being composed of a plurality of magnetizable members, the members of each layer and the adjacent members of different layers being 40 insulated from each other.

5. An extended pole-piece for magnetic closers having a plurality of sections arranged in sufficiently close proximity to each other to provide a substantially continuous magnetic path, but separated by suitable insulating members.

6. An extended pole-piece for magnetic closers, comprising the combination of an upper magnetizable layer contacting with the 45 cores of the magnet, a center layer of insulating material, and a lower magnetizable layer made up of a plurality of sections separated by suitable insulation.

7. The extended pole-piece herein described, comprising the upper and lower members, each composed of a plurality of iron plates separated by insulators, and the center layers composed of a sheet of rubber or other suitable insulating material.

8. In combination, the layer of iron plates a, a³, a⁴, &c., separated by suitable insulating material, the second layer of iron plates, a', a², a⁵, &c., similarly separated, the interposed sheet of insulating material, and insulated tap-bolts securing the whole together.

In testimony whereof I have affixed my signature in presence of two witnesses.

JOSEPH N. THOMAS.
